FLUID PRESSURE MECHANISM

Wilfred A. Eaton, Elyria, Ohio, assignor to Bem-
dix-Westinghouse Automotive Air Brake Com-
pany, Elyria, Ohio, a corporation of Delaware

Application August 4, 1943, Serial No. 497,386

13 Claims. (Cl. 230—2)

This invention relates to fluid pressure supply systems and more particularly to mechanism for supplying fluid pressure under substantially high pressures and for controlling the maintenance of these pressures.

The present invention contemplates a mode of operation wherein the intake side of the fluid compressor is normally maintained at a pressure well above atmospheric pressure, this mode of operation permitting the compressing of fluid at a relatively high pressure at the output side of the compressor without resulting in a corresponding increased pressure ratio, such as would occur in the event such a high pressure were obtained from a single stage compressor in the ordinary manner. It has previously been proposed to employ systems of this general type, but some of these systems have required complicated and expensive mechanism for controlling the pressures in the low and high pressure portions of the system and it is accordingly an object of the present invention to provide mechanism for overcoming these difficulties.

Previous mechanisms of the above nature have in some cases necessitated continuous operation of the compressor against a relatively high pressure even when the desired pressures were established in the low and high pressure portions of the system, and it is accordingly a further object of the present invention to provide means controlled by variations of pressure in the system for unloading the compressor and preventing the compression of further fluid when the desired pressures are established.

Yet another object of the invention is to provide means controlled by variations of pressure in the low pressure portion of the system for controlling the operation of the compressor to alternately compress atmospheric fluid and supply it to the low pressure portion of the system and to recompress fluid from the low pressure portion of the system and supply it to the high pressure portion of the system, together with means controlled by variations of pressure in the high pressure portion of the system for rendering the compressor ineffective to supply further fluid pressure to the system when predetermined desired pressures are reached in the various parts of the system.

Still another object of the invention is to provide in a system of the above type, simple and efficient means for connecting the discharge port of the compressor with the inlet port of the compressor and to prevent the flow of fluid pressure from the high pressure portion of the system to

the inlet port of the compressor during this type of operation.

A further object of the invention is to provide means for preventing the loss of fluid pressure from the system to atmosphere under all conditions of operation.

These and other objects and novel features of the invention will appear more fully hereinafter from the following detailed description when considered in connection with the accompanying drawing, wherein one embodiment of the invention is illustrated.

It is to be expressly understood, however, that the drawing is employed for purposes of illustration only and is not designed as a definition of the limits of the invention, reference being had for this purpose to the appended claims.

In the single drawing, there is illustrated diagrammatically and partially in section, a fluid pressure supply system constructed in accordance with the principles of the present invention.

The system is provided with low and high pressure reservoirs 6 and 7 respectively, together with a fluid compressor 8, which may be of any well-known type, the compressor being provided with a discharge connection 9 and an inlet connection 10, the latter being adapted to receive fluid from the atmosphere through a conduit 11, a conduit 12 connected therewith and a one way check valve 13 having a connection 14 with atmosphere, it being understood that the check valve is so constituted as to permit the flow of fluid pressure from the atmosphere to the inlet port of the compressor and to prevent the flow of fluid pressure in the opposite direction through said connections. The outlet port 9 of the compressor is connected with the low pressure reservoir through a conduit 15 and a conduit 16, the latter conduits being connected as shown by means of a control valve mechanism 17 to be more fully described hereinafter. In order that fluid pressure may be supplied to the high pressure reservoir 7 from the compressor, the conduit 15 is connected with the latter reservoir by means of conduits 18 and 19, the latter being connected by means of a one way check valve 20, so constituted as to permit the flow of fluid pressure from the conduit 18 to the conduit 19 and to prevent the flow of fluid pressure therethrough in the opposite direction.

The valve mechanism 17 is provided with a casing 21, the casing being provided with a chamber 22 connected with the conduit 15, a chamber 23 connected with the low pressure res-

ervoir and a chamber 24 connected with the conduit 18. The chamber 23 is separated from the chamber 22 by means of a partition 25 provided with a centrally located port 26, while the chamber 24 is separated from the chamber 22 by means of a partition 27 provided with a centrally located port 28. The lower end of the port 28 is normally closed by means of a valve 29 provided with an upwardly extending stem 30 slidably mounted in a partition 31 serving to define the upper end of the chamber 24. A suitable diaphragm or pressure responsive member 32 is suitably attached to the upper end of the valve stem 30 and clamped between the casing 21 and a cover plate 33, as shown, the plate being bolted to the casing by means of bolts 34. The diaphragm serves to define in connection with the casing and cover plate, an atmospheric chamber 35 below the diaphragm and a control chamber 36 above the diaphragm, a spring 37, interposed between the lower face of the diaphragm and the upper surface of the partition 31, serving to normally maintain the valve and diaphragm in the position shown. It will thus be seen that with the parts of the valve 17 in the position shown, the valve serves to establish communication between conduits 15 and 16 through chamber 22, port 26 and chamber 23, and to prevent communication between conduits 15 and 18, while on downward movement of the valve in response to the supplying of fluid pressure to the control chamber 36, the valve operates to close the upper end of the port 26 to prevent communication between conduits 15 and 16, and to open the port 28 in order to permit communication between conduits 15 and 18 through chamber 22, port 28 and chamber 24. In order to insure proper action of the diaphragm 32, the chamber 35 is provided with an atmospheric port 38.

In order to control the operation of the valve mechanism 17, a governor of well-known type designated as 39 is associated with the low pressure reservoir, being connected with the reservoir by means of a conduit 40 and with the control chamber 36 by means of a conduit 41, it being understood that the governor is so constructed as to normally prevent communication between conduits 40 and 41 and to permit communication between conduit 41 and an exhaust port, not shown, an increase in the pressure supplied to the governor through the conduit 40 beyond a predetermined value serving to operate the latter to prevent communication between the conduit 41 and the exhaust port and to establish communication between conduits 40 and 41 in order to supply fluid pressure from the reservoir to the control chamber 36, with consequent movement of the valve 17 to the downward position previously described.

It will be understood from the foregoing description that the discharge port of the compressor is normally connected with the low pressure reservoir and disconnected from the high pressure reservoir, and since it is an object of the invention, when a predetermined pressure has been established in the low pressure reservoir, to utilize the fluid in this reservoir to supercharge the compressor by feeding this fluid back into the inlet of the compressor and recompressing this fluid into the high pressure reservoir at a relatively high pressure, means are also provided under the control of the governor 39 for establishing a connection between the low pressure reservoir and the inlet of the compressor at the same time that the valve mechanism 17 is actuated by the

governor 39 to dis-establish the connection between the discharge port and the low pressure reservoir and to establish a connection between the discharge port of the conduit leading to the high pressure reservoir. The low pressure reservoir is accordingly connected with the conduit 11 leading to the inlet port of the compressor by means of conduits 42 and 43, these conduits being interconnected by means of a control valve mechanism 44. The control valve mechanism 44 is provided with a casing 45 having an inlet chamber 46 and an outlet chamber 47, these chambers being separated by means of a partition 48 formed in the casing as shown, and provided with a centrally located port 49. The upper end of the port is normally closed by means of a valve element 50, this valve element being provided with a downwardly extending stem 51 slidably mounted in a partition 52 which serves to define the lower end of the chamber 47. A suitable diaphragm or pressure responsive member 53 is attached to the lower end of the valve stem and clamped at its outer periphery to the lower end of the casing 45 by means of a cover plate 54 attached thereto by means of suitable bolts 55. The diaphragm thus serves in connection with the casing and cover plate to define an atmospheric chamber 56 above the diaphragm having an atmospheric port 57, as well as a control chamber 58 below the diaphragm, the control chamber being connected with the outlet conduit 41 of the governor 39 by means of a conduit 59. The valve is normally maintained in the position shown by means of a spring 60 interposed between the lower face of the partition 52 and the upper surface of the diaphragm 53, a shoulder or stop 61 formed on the valve stem as shown serving to limit the upward travel of the valve in order to prevent the possibility of the latter interfering with the entrance of fluid to the chamber 46 through the conduit 42. Since the control chamber 58 is connected with the outlet conduit 41 of the governor 39 by means of the conduit 59, it will be understood that operation of the governor to supply fluid pressure to the control chamber 36 of the valve 17 will likewise serve to supply fluid pressure in the control chamber 58 of the valve 44, the result being that on operation of the valve 17 to dis-establish the connection between the discharge port of the compressor and the low pressure reservoir and to establish a connection between the discharge port and the conduit leading to the high pressure reservoir, the valve mechanism 44 will simultaneously operate to establish a connection between the low pressure reservoir and the inlet port of the compressor through the conduit 42, the inlet chamber 46, the port 49, the outlet chamber 47, and conduits 43 and 11. Thus on operation of the control valve 17 to connect the discharge port of the compressor with the high pressure reservoir, the valve 44 will be effective to supply fluid pressure from the low pressure reservoir to the inlet of the compressor at a pressure considerably above atmospheric, permitting a relatively high pressure to be delivered to the high pressure reservoir with the compressor operating at a substantially low compression ratio. This type of operation is advantageous in many ways and permits the supplying of a relatively high pressure to the high pressure reservoir without detrimental heating of the compressor which would occur in the event this high pressure were obtained without supercharging the compressor. During the supercharging operation,

it will also be understood that as the pressure in the low pressure reservoir decreases, a point will be reached such that the governor 39 will become effective to again dis-establish the connection between conduits 40 and 41 and to establish a connection between the conduit 41 and atmosphere, this resulting in an exhaust of fluid pressure from the control chamber 36 of the valve 17 as well as the control chamber 58 of the valve 44, with a resultant return of the valves 29 and 50 to the positions shown, whereupon the compressor will draw in fluid from atmosphere and compress it into the low pressure reservoir in order to replace the fluid supplied to the compressor from the low pressure reservoir for supercharging purposes.

It will be obvious that during the operation of a system of the above described type, it will be necessary to provide means of some form to limit the pressure developed in the high pressure reservoir to a safe and predetermined value, and while a safety valve of the conventional type might be utilized to discharge the excess fluid to atmosphere, this type of operation would result in the loss of fluid from the system with the resultant necessity of drawing a corresponding amount of additional fluid through the atmospheric intake of the compressor, and since the fluid in the atmosphere normally contains a considerable amount of moisture or water vapor, this type of operation tends to increase the moisture content in the system and to eventually result in excessive precipitation of moisture within the system, with a resultant tendency toward the formation of ice during low temperature operation which might tend to seriously interfere with the safe and satisfactory operation of the mechanism. To this end, means are also provided for limiting the pressure developed in the high pressure reservoir without exhausting the 40 excess fluid to atmosphere and this means is also utilized to unload the compressor in order to prevent the pumping of fluid to either of the reservoirs when the pressure in the high pressure reservoir is established at a predetermined value, such unloading mechanism including a conduit 62 connected at one end with the conduit 18 and at the other end with the conduit 43 through the medium of a valve mechanism 63. The valve mechanism 63 is provided with a casing 64 having an inlet chamber 65 and an outlet chamber 66 formed therein, the inlet chamber being connected with the conduit 62 and the outlet chamber being connected with the conduit 43. The chambers are separated by means of a partition 67 having a port 68 centrally located therein, this port normally being closed by means of a valve 69 provided with an upwardly extending stem 70 slidably mounted in a partition 71 formed in the casing and serving to define the upper end of the outlet chamber 66. The upper end of the valve stem is provided with a diaphragm 72 suitably attached thereto and clamped at the periphery thereof to the upper end of the casing by means of a cover plate 73 suitably bolted thereto. The diaphragm serves in connection with the casing and the cover plate to define an atmospheric chamber 74 below the diaphragm connected with atmosphere by means of a port 75, as well as a control chamber 76 above the diaphragm. The valve is normally maintained in the position shown by means of a spring 77 interposed between the lower face of the diaphragm and the upper surface of the partition 71, downward movement of the valve from 75

the position shown being limited by means of a stop 78 formed on the stem of the valve in order to prevent the possibility of the valve being forced downward sufficiently to close the upper end of the conduit 62 connected with the chamber 65. The supply of fluid pressure to the control chamber 76 is controlled by the operation of a governor 79, which may be constructed in the same manner as the governor 39. The governor is connected with the reservoir 7 by means of a conduit 80 and with the control chamber 76 by means of a conduit 81, the governor serving normally to establish a connection between the conduit 81 and atmosphere and to prevent communication between conduits 80 and 81, and serving when the pressure in the reservoir 7 exceeds a predetermined value for which the governor may be adjusted, to dis-establish communication between conduit 81 and atmosphere and to establish communication between conduits 80 and 81 to supply fluid pressure from the reservoir to the control chamber 76. The governor 79 is preferably so adjusted as to operate at a considerably higher pressure than the governor 39. As stated heretofore, the system is so arranged that the compressor is initially operative to charge the low pressure reservoir to a predetermined pressure, and to thereafter alternately transfer fluid from the low pressure reservoir to the high pressure reservoir and from atmosphere to the low pressure reservoir to replace fluid which has been transferred therefrom to the high pressure reservoir. The compressor is thus alternately operative to supply fluid to the low and high pressure reservoirs and as this operation continues, the pressure in the high pressure reservoir will increase to a value sufficient to actuate the governor 79 to dis-establish the connection between conduit 81 and atmosphere and to connect the conduit 80 and 81 to supply fluid pressure to the control chamber 76 of the valve 63. Since the above action of the governor can only occur during a rise in pressure in the reservoir, it is obvious that this action will normally occur when the valve 29 of the valve 17 is in its downward position in order to permit the compressor to supply fluid directly to the high pressure reservoir, and when the pressure reaches a value sufficient to operate the governor and supply fluid pressure to the control chamber 76, the valve 68 will be moved downward to establish a connection between conduits 62 and 43, thus serving to connect the discharge port of the compressor with the inlet port of the compressor through conduit 15, the valve mechanism 17, conduits 18 and 62, chamber 65 of the valve 63, port 67, outlet chamber 66, and conduits 43 and 11, any fluid pumped by the compressor thus being returned to the inlet side of the compressor and serving to maintain both the inlet and outlet ports at substantially the same pressure in order to prevent the further supplying of fluid to either of the reservoirs. In order to prevent the possibility of the high pressure fluid in the reservoir 7 from flowing to the conduit 62 and thence to the inlet port of the compressor through the above described connections, the one way check valve 20 interconnecting the conduits 18 and 19 is provided, and serves effectively to prevent loss of fluid from the high pressure reservoir when the compressor is unloaded by the action of the valve 63 under the control of the governor 79. In the event fluid is utilized from the high pressure reservoir or depleted therefrom by leakage, the pressure will eventually drop to such a value

that the governor 19 will again become operative to disconnect conduits 80 and 81 and to connect the latter conduit with atmosphere to exhaust fluid pressure from the control chamber 16 and permit the valve 69 to return to the position shown, thus dis-establishing the connection between the inlet and discharge ports of the compressor and permitting the latter to be effective to supply fluid pressure to one or the other of the reservoirs dependent on the operation of the control valve 17.

The above described system is illustrated as being adapted to supply fluid for the actuation of a fluid motor 82, this motor being provided with a piston 83 slidably mounted therein and adapted for connection with a device to be actuated, not shown, by means of a conventional piston rod 84. Fluid pressure is supplied to the motor through a conduit 85 connected with the reservoir 7 and a conduit 86 connected with the motor, communication between these conduits being controlled by means of a brake valve 87, which may be preferably constructed in accordance with the principles set forth in the patent to Wilfred A. Eaton, No. 2,204,530, dated June 11, 1940. The valve is provided with a brake pedal 88 pivotally mounted thereon by means of a pin 89, and it will be understood on reference to the above patent, that with the pedal in the position shown, the valve is operative to prevent communication between conduits 85 and 86 and to establish communication between conduit 86 and an exhaust port 90, the latter port being connected with the low pressure reservoir by means of a conduit 91, while on downward movement of the pedal, the valve mechanism is operative to dis-establish the connection between conduit 86 and the exhaust port 90 and to establish communication between conduits 85 and 86 to supply fluid pressure to the motor 82 at a pressure substantially proportional to the degree of movement of the brake pedal, movement of the pedal back to the position shown serving to reverse the operation and to exhaust fluid pressure from the motor. In view of the fact that the exhaust port of the valve is connected with the low pressure reservoir, all fluid exhausted from the motor is returned to the system and is not lost to atmosphere, such fluid being recompressed and delivered to the high pressure reservoir. In view of the fact that the low pressure reservoir is normally maintained at a pressure above atmospheric, it will be understood that this pressure will exist at all times in the conduit 91 and that it will be accordingly necessary to provide a spring 92 having sufficient tension to return the piston 83 to the position shown against the back pressure in the low pressure side of the system on release operation of the brake pedal.

There has thus been provided, as heretofore described, a fluid pressure supply system having a low pressure reservoir preferably maintained at a pressure above atmospheric pressure and a high pressure reservoir maintained at a higher pressure, the delivery of fluid from the compressor to these reservoirs being controlled by variations in pressure in both reservoirs in order to maintain a substantially predetermined relationship between the pressures obtaining in the two reservoirs. The compressor is initially operated to receive fluid from the atmosphere and to compress it in the low pressure reservoir, this fluid in turn being returned to the inlet of the compressor to supercharge the latter and permit this fluid to be compressed to a higher degree and delivered to the high pressure reservoir. The

compressor operates to alternately supply fluid to one reservoir or the other until such time as the pressure in the high pressure reservoir is sufficient to render the governor and valve mechanism operative to establish a connection between the discharge port and the inlet port of the compressor, the establishment of this connection serving to unload the compressor and to prevent further delivery of fluid to either of the reservoirs until such time as the pressure conditions in the system are changed sufficiently to render the governor mechanism operative to again load the compressor. In view of the fact that no fluid is taken into the system after the latter is initially charged except for the purpose of replacing leakage, the concentration of water vapor in the system can be maintained at a relatively low value, thus minimizing difficulties which might otherwise occur due to freezing of such moisture in the system. In addition to the foregoing, a single stage compressor may be utilized to pump a relatively high pressure without rendering it necessary for the compressor to operate at an abnormally high compression ratio with resultant heating of the compressor parts. These features all contribute to a type of operation tending to minimize failures due to freezing and tending to increase the life of the compressor and minimize the formation of carbon therein.

While one embodiment of the invention has been shown and described herein with considerable particularity, it will be readily apparent to those skilled in the art that the invention is not limited to the form shown, but may receive a variety of mechanical expressions. Reference will, therefore, be had to the appended claims for a definition of the limits of the invention.

What is claimed is:

40. 1. The combination in a fluid pressure supply system having low and high pressure reservoirs and a compressor provided with inlet and discharge ports, of means for supplying fluid pressure from the compressor to said reservoirs including a normally open connection between said discharge port and the low pressure reservoir, a normally closed connection between said discharge port and the high pressure reservoir, means including a valve controlled by variations of pressure in said low pressure reservoir for closing the first connection and opening the other connection when the pressure in said low pressure reservoir exceeds a predetermined value, and means including a valve controlled by variations in pressure in the high pressure reservoir for establishing a connection between the second named connection and the inlet port of the compressor when the pressure in said high pressure reservoir exceeds a predetermined value.
45. 2. The combination in a fluid pressure supply system having high and low pressure reservoirs and a compressor provided with inlet and discharge ports, of means for supplying fluid pressure from the compressor to said reservoirs including a normally open connection between the discharge port and the low pressure reservoir, a normally closed connection between said discharge port and the high pressure reservoir, means including a valve controlled by variations in pressure in said low pressure reservoir for closing the first connection and opening said other connection when the pressure in said low pressure reservoir exceeds a predetermined value, and means including a valve responsive to variations

- 55.
- 60.
- 65.
- 70.
- 75.

in pressure in the high pressure reservoir for establishing a connection between the second named connection and the inlet port of the compressor when the pressure in said high pressure reservoir exceeds a predetermined value, and means associated with the second named connection for preventing the flow of fluid pressure from the high pressure reservoir to the inlet port of the compressor when the second named connection is connected with the inlet port of the compressor.

3. The combination in a fluid pressure supply system having low and high pressure reservoirs and a compressor provided with inlet and discharge ports, of means for supplying fluid pressure from the compressor to said reservoirs including a normally open connection between said discharge port and the low pressure reservoir, a normally closed connection between said discharge port and the high pressure reservoir, means including a valve controlled by variations in pressure in said low pressure reservoir for closing the first connection and opening said other connection when the pressure in said low pressure reservoir exceeds a predetermined value, and means including a pressure responsive valve serially connected between the first named valve and the inlet port of the compressor and controlled by variations of pressure in the high pressure reservoir for establishing a connection between the discharge port and the inlet port of the compressor when the pressures in said low and high pressure reservoirs exceed predetermined low and higher values respectively.

4. The combination in a fluid pressure supply system having low and high pressure reservoirs and a compressor provided with inlet and discharge ports, of means for supplying fluid pressure from the compressor to said reservoirs including a normally open connection between said discharge port and the low pressure reservoir, a normally closed connection between said discharge port and the high pressure reservoir, means including a valve controlled by variations in pressure in said low pressure reservoir for closing the first connection and opening said other connection when the pressure in said low pressure reservoir exceeds a predetermined value, means controlled by variations in pressure in the high pressure reservoir for establishing a connection between said second named connection and the inlet port of the compressor when the pressure in said high pressure reservoir exceeds a predetermined value, and means including a valve controlled by variations in pressure in the low pressure reservoir for establishing a connection between the latter reservoir and the inlet port of the compressor when the pressure in said low pressure reservoir exceeds said first named predetermined value.

5. The combination in a fluid pressure supply system having high and low pressure reservoirs and a compressor provided with inlet and discharge ports, of means for alternately supplying fluid pressure from the compressor to the low pressure reservoir and from the low pressure reservoir to high pressure reservoir through said compressor and for preventing the compressor from supplying fluid pressure to either of the reservoirs including a normally open connection between the discharge port of the compressor and the low pressure reservoir, a normally closed connection between the discharge port and the high pressure reservoir, a normally closed connection between the low pressure

reservoir and the inlet port of the compressor, a normally closed connection between the second named connection and the inlet port of the compressor, and means for controlling said connections including valvular means responsive to variations in pressure in the low pressure reservoir for closing the first named connection and opening the second named connection and for opening the connection between the low pressure reservoir and the inlet port when the pressure in the low pressure reservoir exceeds a predetermined value and valvular means controlled by variations of pressure in the high pressure reservoir for opening the connection between the second named connection and the inlet port of the compressor when the pressure in the high pressure reservoir exceeds a predetermined value.

6. The combination in a fluid pressure supply system having low and high pressure reservoirs and a compressor provided with inlet and discharge ports, of means for supplying fluid pressure from the compressor to said reservoirs including a normally open connection between said discharge port and the low pressure reservoir, a normally closed connection between said discharge port and the high pressure reservoir, a normally closed connection between said second named connection and the inlet port of the compressor, a normally closed connection between the low pressure reservoir and the inlet port of the compressor, fluid pressure operated valvular means for controlling the first two connections, fluid pressure operated valvular means for controlling the third named connection, fluid pressure operated valvular means for controlling the last named connection, means responsive to variations in pressure in the low pressure reservoir for operating the first named valvular means to close the first named connection and open the second named connection and for operating the last named valvular means to open the last named connection when the pressure in the low pressure reservoir exceeds a predetermined value and for permitting operation of said first and last named valvular means in the reverse direction when the pressure in said low pressure reservoir drops to a lower predetermined value, and means responsive to variations in pressure in the high pressure reservoir for operating the second named valvular means to open the third named connection when the pressure in the high pressure reservoir exceeds a predetermined value and to close said connection when the pressure in the high pressure reservoir drops to a lower predetermined value.

7. The combination in a fluid pressure supply system having low and high pressure reservoirs and a compressor provided with inlet and discharge ports, of means for supplying fluid pressure from the compressor to said reservoirs including an atmospheric connection to the inlet port, a normally open connection between said discharge port and the low pressure reservoir, a normally closed connection between said discharge port and the high pressure reservoir, means including a valve controlled by the variations in pressure in said low pressure reservoir for closing the first connection and opening said other connection when the pressure in said low pressure reservoir exceeds a predetermined value, means including a valve responsive to variations in pressure in the high pressure reservoir for connecting the second named connection with the inlet port of the compressor when the pressure in the high pressure reservoir exceeds a predetermined value,

valvular means controlled by variations in pressure in the low pressure reservoir for connecting the low pressure reservoir with the inlet port of the compressor when the pressure in said low pressure reservoir exceeds said first named predetermined value, and means for preventing the flow of fluid pressure from the inlet port of the compressor to atmosphere when said connections are established between said inlet port and said low pressure reservoir and between said inlet port and said second named connection.

8. The combination in a fluid pressure supply system having low and high pressure reservoirs and a compressor provided with inlet and discharge ports, of means for supplying fluid pressure from the compressor to said reservoirs including a normally open connection between said discharge port and the low pressure reservoir, a normally closed connection between the discharge port and the high pressure reservoir, a normally closed connection between the low pressure reservoir and the inlet port of the compressor, a normally closed connection between the second named connection and the inlet port of the compressor, valvular means controlled by variations in pressure in the low pressure reservoir for closing the first named connection and opening the second and third named connections when the pressure in said reservoir exceeds a predetermined value, and valvular means controlled by variations in pressure in the high pressure reservoir for opening said last named connection whenever the pressure in said high pressure reservoir exceeds a higher predetermined value.

9. The combination in a fluid pressure supply system having low and high pressure reservoirs and a compressor provided with inlet and discharge ports, of means for supplying fluid pressure from the compressor to said reservoirs including a normally open connection between the discharge port and the low pressure reservoir, a normally closed connection between said discharge port and the high pressure reservoir, a normally closed connection between the low pressure reservoir and the inlet port of the compressor, a normally closed connection between said second named connection and the inlet port of the compressor, valvular means controlled by variations in pressure in the low pressure reservoir for closing the first named connection and opening the second and third named connections when the pressure in said reservoir exceeds a predetermined value, valvular means controlled by variations in pressure in the high pressure reservoir for opening said last named connection when the pressure in said high pressure reservoir exceeds a higher predetermined value, and means associated with said second named connection for preventing the flow of fluid pressure from the high pressure reservoir to the inlet port of the compressor through said connections and second named valvular means.

10. The combination in a fluid pressure supply system having low and high pressure reservoirs and a compressor provided with inlet and discharge ports, of means for controlling the supply of fluid pressure from said compressor to said reservoirs for alternately supplying fluid pressure to the low pressure reservoir, for supplying fluid pressure from the low pressure reservoir to the high pressure reservoir through the compressor, and for preventing the supplying of fluid pressure to either of said reservoirs by the compressor, including a transfer valve controlled by variations of pressure in the low pressure reservoir for alter-

nately connecting the discharge port of the compressor with the low and high pressure reservoirs respectively, valvular means controlled by variations in pressure in the low pressure reservoir for alternately connecting and disconnecting the low pressure reservoir with the inlet port of the compressor, and valvular means controlled by variations of pressure in the high pressure reservoir for alternately connecting the discharge and inlet ports of the compressor through the first named valvular means.

11. The combination in a fluid pressure supply system having low and high pressure reservoirs and a compressor having inlet and discharge ports, of means for controlling the flow of fluid pressure from the compressor to said reservoirs including a valve having a connection with the discharge port, and connections with both of said reservoirs, means for normally maintaining said valve in a position to permit the flow of fluid pressure from the discharge port to the low pressure reservoir and to prevent the flow of fluid pressure to the high pressure reservoir, means including a pressure responsive member for moving said valve to prevent the flow of fluid pressure from the discharge port to the low pressure reservoir and to permit the flow of fluid pressure to the high pressure reservoir when the pressure in the low pressure reservoir exceeds a predetermined value, a connection between the low pressure reservoir and the inlet port, means including a valve for normally closing said connection, means including a pressure responsive member for moving said second valve to open position when the pressure in said low pressure reservoir exceeds said predetermined value, and means including a valve controlled by variations of pressure in the high pressure reservoir for establishing a connection between said discharge port and inlet port through said first named valve when said valve is positioned to permit the flow of fluid pressure from the discharge port to the high pressure reservoir and when the pressure in the latter exceeds a predetermined value higher than the first named predetermined value.

12. The combination in a fluid pressure supply system having low and high pressure reservoirs and a compressor provided with discharge and inlet ports, of means for controlling the supply of fluid pressure to said reservoirs including a valve operable in one position to connect the discharge port with the low pressure reservoir and in a second position to disconnect the discharge port from the low pressure reservoir and to connect said port with the high pressure reservoir, means including a second valve operable in one position to prevent communication between the low pressure reservoir and the inlet port and in a second position to establish a connection between the low pressure reservoir and the inlet port, means including a third valve operable in one position to prevent the flow of fluid pressure from the discharge port to the inlet port and in a second position to establish communication between said ports, and means for controlling the operation of said valves including means responsive to variations of pressure in the low pressure reservoir for moving said first and second valves to the second position when the pressure in the low pressure reservoir exceeds a predetermined value and means responsive to variations of pressure in the high pressure reservoir for moving said third valve to the second position when the pressure in the high pressure reservoir exceeds a higher predetermined value.

13. The combination in a fluid pressure supply

system having low and high pressure reservoirs and a compressor provided with discharge and inlet ports, of means for controlling the supply of fluid pressure to said reservoirs including a valve operable in one position to connect the discharge port with the low pressure reservoir and in a second position to disconnect the discharge port from the low pressure reservoir and connect said port with the high pressure reservoir, means including a second valve operable in one position to prevent communication between the low pressure reservoir and the inlet port and in a second position to establish a connection between the low pressure reservoir and the inlet port, means for controlling the operation of said valves including

10 15

means responsive to variations of pressure in the low pressure reservoir for moving said first and second valves to said second positions when the pressure in said low pressure reservoir exceeds a predetermined value, and means for establishing a connection between the discharge port and inlet port when said first valve is in said second position including a third valve connected in serial relationship with said first valve between said ports and means responsive to variations of pressure in said high pressure reservoir for opening said third valve when the pressure in the high pressure reservoir exceeds a higher predetermined value.

WILFRED A. EATON.
